UNITED STATES PATENT OFFICE

2,518,060

SHOWER BATH CABINET WITH ROTARY CLOSURE MEANS

David T. Pickles, Washington, N. C.

Application February 3, 1948, Serial No. 6,057

2 Claims. (Cl. 4—146)

2

Figure 2 is a vertical sectional view of the cabinet with the door open.

Figure 3 is a sectional view at line 3—3 of Fig. 1.

5 Figure 4 is a horizontal sectional view at line 4—4 of Fig. 1 with the door closed; and Figure 5 is a similar view with the door in open position.

10 Figure 6 is a transverse horizontal sectional view at the top portion of the cabinet showing the annular supporting track for the rotary cylindrical door; and

15 Figure 7 is a horizontal sectional view showing the cabinet made of molded plastic material, and with the rotary door closed.

20 The enclosure or housing of the bathing appliance forms a cabinet or shower bath having a bottom tub-portion, and suitable materials are employed in the manufacture of the cabinet and its rotary hand manipulated door or closure, such as non-rusting metals, as well as molded plastic materials. In the principal views of the drawings, the cabinet 1 is of substantially cylindrical shape and provided with a pair of parallel rearwardly extending side walls 2, 2, which, together 25 with a rear wall 3 form a recess or alcove 4 offset from the cabinet, and the base 5 provides an inclined or sloping floor for the structure, which preferably has an open top.

25 The cabinet is provided with a front door opening or entrance 6 that terminates at its lower end a substantial distance above the floor to provide a combing or upright flange 7 to form a front guard or shield to confine water within the cabinet.

30 The fittings or trim for the shower cabinet include a shower head 8, and control valves 9 and 10 for hot and cold water respectively, and a conventional diverting valve 11, mounted in the back wall of the cabinet and located in the recess or alcove 4 for ready access of the bather when the cabinet is closed. The diverting valve 11 tempers the water at the outlet, close to the floor or base of the cabinet, and the water is then diverted to the shower head, as usual. After the shower and 45 after the control valves have been closed, the diverting valve automatically returns to its original safety position; and the water from the shower drains off from the inclined or sloping floor through a drain 12 as is customary.

35 Before the bath and after the bather enters the cabinet, and also before the bather can have access to the water controls located in the recess or alcove, the front entrance or opening of the cabinet must be closed to prevent escape of water 45 from the interior of the cabinet. For this purpose

1 My present invention relates to the general class of baths and closets of the cabinet type, and more specifically to an improved shower bath cabinet with rotary closure means, which while well adapted for domestic use, is especially designed for public services in hotels, inns, clubs, and other institutions and associations. When this type of public service is provided many careless and indifferent users by their actions create damaging and unsanitary conditions in the equipment; and to remedy these undesirable and objectionable conditions I provide a self-conserving appliance that must receive correct and proper attention on the part of the user to insure its operation. For instance, the water controls are located and arranged in position to be inaccessible to the bather unless and until he has closed the appliance against splashing of water from the interior to the exterior of the cabinet, thus eliminating the undesirable wetting of walls and floors.

2 In the physical embodiment of my invention minimum number of parts are employed, which may with facility and low cost of production be manufactured, and the parts may be assembled and installed with convenience to afford an appliance that is simple in operation, durable, and efficient in the performance of its required functions.

3 The invention consists in certain novel features of construction and combinations and arrangements of parts involving a substantially cylindrical housing or cabinet enclosing a complementary rotary closure or door each having an entrance opening, together with means for supporting and guiding the rotary closure as it is manipulated by hand, as will hereinafter be described in detail, and more particularly set forth in the appended claims.

4 In the accompanying drawings I have illustrated a complete example of a physical embodiment and installation of my invention wherein the parts are combined and arranged in accord with one mode I have devised for the practical application of the principles of the invention. It will, however, be understood that changes and alterations are contemplated and may be made in these exemplifying drawings and mechanical structures, within the scope of my claims, without departing from the principles of the invention.

5 Figure 1 is a view in front elevation of a shower in which my invention is embodied, with the door closed.

I employ a substantially cylindrical shell or rotary turret forming a rotary door 13 of ample size to accommodate the bather when taking a shower.

The rotary door is operated by the bather grasping a handle 14 on the door, and the door is provided with an upright open slot 15 forming an entrance opening complementary to the opening in the cabinet; and in the rotary movement of the door its entrance opening may register with the cabinet entrance and the recess alternately.

The rotary door or shell is supported or suspended within the cabinet by means of an overhead annular or circular track 16 rigidly mounted, as by brackets 17, on the upper end or top portion of the rotary door, and this track moving with the door is adapted to travel on a series of circumferentially spaced rollers 18 journaled in brackets or hangers 19 rigidly mounted on 20 and near the top of the wall of the cabinet.

For guiding and stabilizing the rotary movement of the suspended door, the door, on its outer side, is equipped with a horizontal series of circumferentially spaced rollers 20 that travel in an annular guide channel or track 21; and it will be apparent that the bather may step over the guard 7, through the registering entrance openings 6 and 14 into the rotary door. The door may then be rotated or rolled around to bring its opening 14 into register with the front portion of the back recess or alcove, thus giving the bather access to the control valves of the shower.

After the shower, and after the control valves have been closed the door is turned on its rollers to bring its opening into register with the front opening of the cabinet, and the bather steps out of the cabinet, leaving the cabinet open for the next bather.

In Fig. 7 the cabinet 22 may be fashioned from molded plastic material, with a back recess, and two opposed curved interior faces 23, to accommodate the rotary cylindrical door or shell, and it will be understood that other changes and alterations may be made in the physical embodiment of my invention.

Having thus fully described my invention, what I claim as new and desire to secure by Letters Patent is:

1. In a shower-bath, the combination with a cylindrical cabinet having an out-set recess with water control devices and a front entrance opening, of a cylindrical rotary door having an entrance opening adapted to register with the cabinet opening, an over-head annular track mounted on the door within the cabinet, a series of circumferentially spaced rollers journaled in the cabinet for supporting the track, a lower annular channel-shaped track mounted within the cabinet, and a series of circumferentially spaced rollers journaled on the exterior of the door for travel in said annular track.

2. The apparatus as described in claim 1, where-in said door closes said outset recess to prevent access to said water control devices when the entrance opening in said door is in registry with the cabinet opening.

DAVID T. PICKLES.
